UNITED STATES PATENT OFFICE.

ROBERT G. ARCHER, SR., AND ROBERT G. ARCHER, JR., OF FORT WASHINGTON,
PENNSYLVANIA.

DESIGN FOR A FLAG HOLDER FOR AUTOMOBILE RADIATORS.

Application filed November 17, 1925. Serial No. 15,442. Term of patent 3½ years.

To all whom it may concern:

Be it known that we, ROBERT G. ARCHER, Sr., and ROBERT G. ARCHER, Jr., citizens of the United States, residing at Fort Washington, in the county of Montgomery and State of Pennsylvania, have invented a new, original, and ornamental Design for Flag Holder for Automobile Radiators, of which the following is a specification, reference being had to the accompanying drawing, forming a part thereof.

Figure 1 is a front elevational view of an automobile radiator attachment, showing our new design.

Figure 2 is a vertical section of the same.

We claim:—

The ornamental design for a flag holder for automobile radiators substantially as shown.
